DESIGN FOR A LAPEL ORNAMENT OR SIMILAR ARTICLE

Arthur Bernecker, Hempstead, N. Y.

Application July 25, 1947, Serial No. 140,509

Term of patent 7 years

(Cl. D45—19)

To all whom it may concern:

Be it known that I, Arthur Bernecker, a citizen of the United States, residing in Hempstead, county of Nassau, and State of New York, have invented a new, original, and ornamental Design for a Lapel Ornament or Similar Article, of which the following is a specification, reference being had to the accompanying drawings, forming a part thereof, in which

Fig. 1 is a top plan view of a lapel ornament or similar article, showing my new design;

Fig. 2 is a bottom plan view thereof; and

Fig. 3 is a side elevational view thereof.

I claim:

The ornamental design for a lapel ornament or similar article, as shown.

ARTHUR BERNECKER.
